US0D1006776S

(12) **United States Design Patent** (10) **Patent No.:** **US D1,006,776 S**
(45) **Date of Patent:** **** Dec. 5, 2023**

(54) **SPEAKER**

(71) Applicant: **ENCORE USA, INC.**, La Puente, CA (US)

(72) Inventor: **Xiaoyan Ming**, Shenzhen (CN)

(73) Assignee: **ENCORE USA, INC.**, La Puente, CA (US)

(**) Term: **15 Years**

(21) Appl. No.: **29/911,109**

(22) Filed: **Aug. 29, 2023**

(51) LOC (14) Cl. **14-01**

(52) U.S. Cl.

USPC **D14/204**

(58) **Field of Classification Search**

USPC D14/159, 185, 188, 194, 204, 217, 218, D14/219, 220, 221, 222, 224, 224.1, 225, D14/227, 228, 229, 259, 299, 432, 465, D14/483

(57) **CLAIM**

The ornamental design for a speaker, as shown and described.

DESCRIPTION

FIG. 1 is a front perspective view of a speaker, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the speaker, that form no part of the claimed design.

1 Claim, 8 Drawing Sheets
